Primary Examiner — Mimosa De

(57) **CLAIM**

The ornamental design for a sun lounger, as shown and described.

DESCRIPTION

FIG. 1 is a front and top perspective view of a sun lounger, showing my new design;

FIG. 2 is a rear and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a sun lounger of FIG. 1 in a use state;

FIG. 9 is an enlarged view of the portion, labeled '9' of FIG. 2; and,

FIG. 10 is an enlarged view of the portion, labeled '10' of FIG. 2.

The broken lines depict portions of the sun lounger in which the design is embodied that form no part of the claimed design.
